ELEMENT FOR CORRECTING ELECTRON-
OPTICAL SYSTEMS

Adrianus Cornelis van Dorsten, Eindhoven, Netherlands, assignor, by mesne assignments, to North American Philips Company, Inc., New York, N.Y., a corporation of Delaware

Application March 14, 1956, Serial No. 571,458

Claims priority, application Netherlands March 15, 1955

9 Claims. (Cl. 250—49.5)

When the field in an electron-optical system is not truly radially symmetrical, the image produced by such a system exhibits astigmatism. As is well-known the detrimental influence of the asymmetry can be eliminated by means of correcting elements which are referred to as "stigmators." The invention relates to a novel stigmator, which offers certain advantages over the known stigmators, as will be seen from the description.

A stigmator in accordance with the invention comprises four or a greater even number of pole pieces of electrically conductive magnetizable material which are arranged symmetrically about the same part of an axis and each are insulated electrically from the two adjacent ones. Said pole-pieces are provided with cylindrical pole faces the generatrices of which are parallel to the axis.

The stigmator must be so arranged that its axis coincides with the optical axis of the system to be connected. The pole pieces must be magnetized to an equal extent so that the magnetic polarity of each pole-face is opposed to that of the two adjacent ones. In addition, an equal electric potential must be applied between each pair of adjacent pole pieces so that pole faces of equal magnetic polarity are at the same potential.

By controlling the potential differences between the pole pieces and the magnetic field strength, astigmatism in any direction and of different values can be eliminated without the correcting elements or part thereof being moved.

The line along which the pole faces intersect a plane at right angles to the axis may be shaped into various forms. It is of advantage for the pole pieces to be convex. It has been found that the optimum effect of the stigmator in accordance with the invention is ensured by shaping the cross-section of the pole-faces into the form of two associated equilateral hyperbolas.

A stigmator in accordance with the invention comprising four pole pieces behaves as a combination of two cylindrical lenses in the same space, an electrostatic and a magnetic lens. The sagittal planes of said cylindrical lenses are at an angle of 45° with one another.

In order that the invention may be readily put into effect, a number of structural embodiments will now be described in detail with reference to the accompanying drawings, in which:

Fig. 1 is a part plan view, part sectional view of such an embodiment, viewed in the direction of the axis,

Fig. 2 is partly a side elevation of the same element, partly a sectional view thereof taken along a plane passing through the axis,

Fig. 3 is a part plan view, part sectional view of a second embodiment of a stigmator in accordance with the invention, viewed in the direction of the axis.

Fig. 4 is a cross-sectional view of the element shown in Fig. 3 taken along the line IV—IV.

Figs. 5 and 6 show a third embodiment similarly projected,

Fig. 7 is a cross-sectional view of a stigmator in accord-

ance with the invention provided with concave polefaces, Fig. 8 is a longitudinal sectional view of the element shown in Fig. 7 taken along the line VIII—VIII.

Fig. 9 illustrates the last-mentioned embodiment, and Fig. 10 is a diagrammatic cross-sectional view of an electron microscope in accordance with the invention.

In Figs. 1 and 2, the four convex pole pieces are designated 1, 2, 3 and 4. They are made of a soft steel frequently used to manufacture magnetic electron lenses. They are interconnected magnetically by ferromagnetic coil-cores 5, 6, 7 and 8. Said cores are made of a ferromagnetic insulating material, such as for example, one of the ferrites commercially available under the trade name "ferroxcube." These materials are fully described in U.S. Patents 2,452,529, 2,452,530 and 2,452,531. They have the composition MFe_2O_4 in which M is a bivalent metal such as copper, nickel, zinc, magnesium, etc. These materials exhibit very low magnetic losses and have a high resistivity. Coil windings 9, 10, 11 and 12 are provided on said cores.

The pole faces are arranged symmetrically about the axis 13. They are provided with cylindrical convex pole faces 14, 15, 16 and 17, the generatrices of which are parallel to the axis 13. In the operation of the stigmator, the current passing through the coil windings 9, 10, 11 and 12 must be so directed that two adjacent coil cores are magnetized in opposite senses. Thus, the successive pole faces 14, 15, 16 and 17 are given alternate polarities: when 14 produces a north pole, 15 produces a south pole, 16 a north pole again and 17 a south pole again. Consequently the magnetic line of force will be symmetrical and at right angles to the axis 13.

In addition, an electric potential is applied between the pole pieces 1 and 2. An equal potential difference is applied between the pole pieces 3 and 2 and between the pole pieces 3 and 4. The pole pieces designated by odd reference numerals are at the same potential which differs from the common potential of the pole pieces designated by even reference numerals. This results in the production of an electric field the lines of force of which coincide with the magnetic lines of force. Since the value of the potential must be different for any direction and value of the astigmatism to be compensated, the potential is made controllable, for example between a few hundreds of volts negative and positive. For the same reason the magnetizing current of the coils is also made variable so that the magneto-motive force can be controlled, for example between 100 ampere-turns negative and positive.

The two fields, the electric and the magnetic field, each act as a cylindrical lens. However, the direction of the refractive force at a predetermined point in space is not the same for the two cylindrical lenses. When the curves at which the pole faces 14, 15, 16 and 17 intersect the common principal plane of the two cylindrical lenses are in the form of two associated equilateral hyperbolas, it can be proved mathematically that the sagittal planes of said lenses are at an angle of 45° with one another.

The astigmatism of an optical system, for example of an electron lens, produced by an insufficient degree of symmetry of the field boundaries can be eliminated with the aid of a cylindrical lens. By rotating this lens about the optical axis it can be moved to the position in which it eliminates the influence upon the image of the asymmetry of the optical system to be corrected, provided that the lens is of suitable power. Starting from the optimum effect of this cylindrical lens, the minimum effect is obtained by rotating it through an angle of 45° only. The same effect can be produced by using a system of two cylindrical lenses of adjustable power the azimuthal angles of which differ by 45°. This requirement is satisfied by

the correcting element in accordance with the invention which has the advantage that it need not be rotated at all. In order to adjust the element to the optimum effect, the power of the two component lenses is changed in opposite senses (so that the resulting lens is rotated) until the remaining astigmatism exhibits a minimum value. Subsequent proportional variation of the strength of the two fields permits of entirely eliminating the astigmatism.

When the cross-section of the pole faces is not shaped into the form of a true hyperbola, the effect of the correcting element is less complete, but nevertheless the use of pole pieces the shape of which does not deviate excessively from the theoretically correct form provides an improvement which is sufficient in practice. The theoretically correct form may, for example, be approximated to by the use of a circular cross-section.

In the embodiment shown in Figs. 1 and 2, the coil-cores are arranged tangentially. They may alternatively be arranged radially. The latter arrangement is shown in Figs. 3 and 4. The pole pieces are designated 18, 19, 20 and 21. The pole faces 22, 23, 24 and 25 are shaped similarly to those shown in the first embodiment. The coil-cores 26, 27, 28 and 29 in this arrangement are made of the same material as the pole pieces and are interconnected by a yoke 30 made of the same material. In order, however, to permit a voltage to be set up between the pole pieces, the yoke is provided with gaps 31, 32, 33 and 34 which are filled with electrically insulating magnetizable material. The coil windings are designated 35, 36, 37 and 38. The current must pass through said windings in alternately opposite senses so that the magnetic flux of, for example, the core 26, starting from the pole-face 22, is closed for one half through the pole piece 19 and the insulator 31 and for the other half through the pole piece 21 and the insulator 34.

As an alternative, a stigmator in accordance with the invention may be produced in which the coil turns are at right angles to the axis of the element. Figs. 5 and 6 show an embodiment of this arrangement. The magnetic system in this embodiment comprises two inter-engaging equal parts. Said parts each consist of a flat annular member (39, 40) having two diametrically opposed projecting thickened portions (41, 42 and 43, 44 respectively) the size of which in the axial direction also exceeds that of the remaining part of the member and the cross-section of which in a plane at right angles to the axis is shaped in the form of the two curves of an equilateral hyperbola cut off by a concentric circle 45. The diameter d_1 of the circle 45 is less than the inner diameter d_2 of the members 39 and 40. The members are arranged coaxially with one another, one being reversed relatively to the other, and one pair of thickened portions is arranged symmetrically with respect to the other pair. A ferromagnetic annular member 46 made from insulating material spaces the members 39 and 40 apart. The inner diameter d_3 of the member 46 which is arranged coaxially with the members 39 and 40 is larger than d_2 . In the space between the member 46 and the parts of the thickened portions 41 to 44 which project beyond the surface of the members 39 and 40, a magnetizing coil 47 is arranged. Since d_1 is less than d_2 , there is a gap between the thickened portion 41 and 42 and the inner wall of the member 39 and likewise between the thickened portions 43 and 44 and the member 40. As a result, magnetic poles are produced when a current passes through the coil 47. The hyperbolic planes of 41 and 42 are given one magnetic polarity and those of 43 and 44 the other magnetic polarity, so that a magnetic cylindrical lens is produced. Between the members 39 and 40 an electric potential can be set up in order to make the system into an electrostatic cylindrical lens.

An alternative embodiment of a stigmator in accordance with the invention, in which the shape of the pole faces is considerably different from that in the embodiments so far described, is shown in Figures 7 and 8. In this

embodiment, the pole faces 48, 49 and 50 and 51 are shaped into a circular cylinder. Fig. 9 illustrates the reason why satisfactory results can nevertheless be obtained with this arrangement.

When of the field produced between the hyperbolic pole faces of the above-described embodiments the field strength in the points of a circle situated in a plane at right angles to the axis and having the centre in said axis is shown in a graph on rectangular coordinates as a function of the angle between the radius vector and a fixed diameter, a sinusoidal line is produced.

The variation of the potential along the circular cross-section of the pole faces 48 to 51 can be represented by the rectangular wave-form line 52 of Fig. 9. The function represented by said line can be resolved according to Fourier into a sinusoidal function and a plurality of harmonics. For a circle having a slightly smaller radius, a curve is obtained from which the highest harmonics have disappeared and as the radius is made smaller more harmonics will disappear. In a circle having a very small radius they have disappeared almost entirely, so that substantially only a sinusoidal function 53 will be left having the same passages through zero as the initial line 52. Consequently, in the proximity of the axis the variation of the field strength is approximately equal to that which is found throughout the entire field with hyperbolic pole faces. Thus, when the radius of the cylinder constituted by the pole faces is large compared with that of the cross-section of the electron beam upon which the fields must act, the shape shown in Fig. 7 is useful in practice.

The stigmator shown in Figs. 7 and 8 substantially comprises two concentric cylinders 54 and 55 made of ferro-magnetic metal. The outer cylinder tapers towards the top and at this top is provided with two windows which each occupy an amount of space slightly larger than one quarter of the periphery. In said windows tags 56 and 57 are arranged which project upwards beyond the edge of the inner cylinder and each occupy an amount of space slightly smaller than one quarter of the periphery. The tops of the tags are slightly spaced away from the upper edge of the windows. Hence the two cylinders are not in contact with one another, although the diameters of their upper parts are equal.

The space between the cylinders, in which space a magnetizing winding 58 is arranged, is closed by a ferro-magnetic electrically insulating annular member 59. This member establishes a direct connection between the cylinders for the magnetic flux which produces magnetic poles at the faces 48 to 51.

It will be obvious that in all the embodiments described the entire ferro-magnetic may consist of electrically insulating material (ferroxcube), provided that the pole faces are coated with a conductive material so that an electric potential can be set up between said faces.

Fig. 10 is a sectional view of an electric microscope provided with a stigmator in accordance with the invention.

The outer wall of said microscope is a steel tube 60 into the upper end of which an electrode system 61 is introduced which acts to produce the electron beam which passes through the entire microscope along the axis of the tube 60. The microscope is provided with three magnetic lenses: a condenser 62, an objective 63 and a projection lens 64. The design and the operation of said members are assumed to be known. In the objective 63, an object 65 is arranged, an image of which is produced by the electron beam upon the glass window 66 which is coated with a layer 67 of fluorescent material.

According to the invention, between the objective and the projection lens provision is made of the correcting element 68 which serves to eliminate the astigmatism of the objective in an optimum manner.

In order to permit of setting up a potential between the poles of the element 68, electric conductors 69 are

secured to this element and passed out through the wall 60. In addition, provision is made of electric conductors 70 which act to supply current to the magnetizing coils. By adjusting the potential and the current the power of the two cylindrical lenses produced by the element can be adjusted. This electric adjustment replaces the known adjustment by means of displacement in the tube of metal correcting members. This means a considerable simplification.

Since the electrostatic cylindrical lens exhibits no spherical aberration and the magnetic lens shows only little spherical aberration, the electron beam in the stigmator may have a large cross-section, while a comparatively large distance between the correcting element and the lens with which it cooperates is not inconvenient per se. For the same reason, an increase in the axial size of the element does not adversely affect the image quality. A comparatively large size in the direction of the axis is even of advantage since it reduces the influence of inconvenient marginal fields.

However, it is desirable for other reasons that the distance between the stigmator and the objective be small compared with that between the stigmator and the production lens, for the smaller the latter distance is at a predetermined distance between the objective and the production lens, the stronger the stigmator must be magnetized in order to enable it to eliminate the astigmatism, but the stronger its influence becomes upon the magnification produced by means of the system to be corrected (obviously in one direction only).

By increasing the spacing between the stigmator and the projection lens, the distortion of the image is reduced. For this reason the stigmator is embedded in the ferromagnetic of the objective in the microscope shown in Fig. 10.

What is claimed is:

1. An electron optical system for an electron microscope having a given optical axis comprising electron beam producing means, an electron lens system for focussing the electron beam which introduces astigmatism into the focussed beam along said axis, a plurality of pairs of spaced pole members each of magnetizable material disposed symmetrically about said optical axis for compensating for the astigmatism introduced into the beam by the electron lens system, each of said pole members having a cylindrical pole face

the generatrix of which is parallel to said axis, a member connecting each of said pole members to one another and consisting of an electrically-insulating ferromagnetic material having a composition MFe_2O_4 in which M is a bivalent metal, means to alternately polarize each of said pole members in an opposite sense, means to apply equal electrical potential differences between adjacent pole members, and means for varying the potential difference between and the field strength of successive pairs of pole members.

2. An electron optical system as claimed in claim 1 in which the electron lens system is a magnetic lens system.

3. An electron-optical system as claimed in claim 1 in which the cylindrical pole face is convex.

4. An electron-optical system as claimed in claim 3 in which a section of each pair of pole faces forms two associated hyperbolas in a plane at right angles to the common axis.

5. An electron-optical system as claimed in claim 3 in which the pole-face is a circular cylinder.

6. An electron-optical system as claimed in claim 1 in which the pole member polarizing means is a coil disposed on said pole and has a given axis which is tangent to a circle concentric with the common axis and passes through said pole member.

7. An electron-optical system as claimed in claim 1 in which each pair of pole members together comprises two coaxial electrically conductive annular members secured together by a yoke of electrically insulating ferromagnetic material having a composition MFe_2O_4 in which M is a bivalent metal.

8. An electron-optical system as claimed in claim 7 in which the pole members are polarized by a coil disposed between the annular members.

9. An electron-optical system as claimed in claim 7 in which the pole members are polarized by a coil surrounding the annular members.
